APPLICATOR

Clarence J. Davies, Detroit, Mich., assignor to National Automotive Fibres, Inc., Detroit, Mich., a corporation of Delaware

Application June 5, 1939, Serial No. 277,555

12 Claims. (Cl. 91—49)

The present invention relates to floor covering, and more particularly to novel apparatus for applying adhesive.

For purposes of illustration, I have shown and described herein the assembly of a floor covering for an automotive vehicle. Floor covering of this type comprises carpeting cut to predetermined shape and attached to insulating padding material. The padding material is shown here as taking the form of a felted or otherwise fabricated pad of coarse fibers, such for example as jute or sisal.

In order to adhere a pad of the type referred to above to a carpet material, it is necessary to apply adhesive liberally to either the carpet or the pad. This is for the reason that the pad has a rough surface which requires a considerable amount of adhesive to result in firm adhesion with another article.

Prior to my invention efforts were made to apply adhesive with an applicator roll, but it was considered necessary to have the cement quite thin in order to avoid loading up of the applicator roll with loose fibers. This necessitated the use of a cement with a naphtha or other volatile solvent in order to shorten the drying time necessary to bring the cement to the tacky state where one surface would adhere to another. As an alternative, where a water solvent cement was employed, it was necessary to employ a long drying time, and when employing low viscosity cements it was difficult to retain the solids on the surface to provide satisfactory adhesion.

The use of thin adhesives employing naphtha or other volatile solvents was highly objectionable from a fire hazard and cost standpoint.

Another objection to the use of thin cements as applied in a manner known to the prior art, was that the cements were pressed into the coarse fibrous surface; their low viscosity accentuating this characteristic rather than being deposited more directly on the surface where they would do the most good. According to the present apparatus, I provide an applicator roll which is adapted to apply as thick a coating of adhesive fluid as desired to a surface of the pad, and to do this uniformly and in a manner to overcome difficulties previously supposed to be inherent in such apparatus.

The applicator roll employed according to the present invention is of vitreous material or of a material having similar surface characteristics, such for example as marble, or the like. By employing an applicator roll of this type, and

by rotating the roll against the direction of feed of the pad, the adhesive is wiped off the roll onto the surface of the pad. This is to be contrasted with the application in which the adhesive is pressed into the roll and transfer from the roll to the pad depends primarily on difference in adhesion between the roll and the pad. Furthermore, by employing the present method, a thick water solvent adhesive may be applied in substantially as tacky a condition as desired, so that the coated pad may be applied directly to the carpet section without intervening drying time.

With the foregoing general remarks in mind, it is an object of the present invention to provide novel apparatus for applying adhesive to articles on a conveyor.

It is a further object of the present invention to provide novel mechanism for applying thick coatings of adhesive to coarse fiber pads.

It is a further object of the present invention to provide novel means for controlling the application of adhesive from an applicator roll to travelling articles.

It is a further object of the invention to provide novel apparatus for automatically applying substantially any amount of fluid to a travelling surface.

Other objects of the invention will be apparent as the description proceeds, and when taken in conjunction with the accompanying drawings wherein:

Fig. 1 is a side elevation of my applicator;

Fig. 2 is a section on the line 2—2, Fig. 1;

Fig. 3 is an enlarged side elevation partly in section of the applicator means; and

Fig. 4 is a section on the section line 4—4, Fig. 2.

Referring first to Fig. 1, I illustrate the complete applicator apparatus which comprises a pad conveyor indicated generally at 10.

Indicated generally at 14 is apparatus for applying adhesive to the pad sections. This mechanism will subsequently be described in detail.

Referring now particularly to Fig. 1, suitable frame elements 22 support the conveyors previously referred to. The pad conveyor 10, which may comprise a flexible belting of canvas or the like, is led around guide rollers, such as roller 24 and advances over a table section 25 which supports the conveyor. An idle supporting roller 28, seen in Figs. 1 and 2, may be employed if desired. As indicated in Fig. 1, the roller 24 is preferably mounted for adjustment longitudi-

nally. In order to vary the tension on the conveyor 10, suitable adjusting means are provided, indicated generally at 26. A motor (not shown) is adapted to drive the conveyor 10 through conventional drive means.

Referring now specifically to Figs. 1 to 4, I provide novel mechanism for controlling the application of adhesive to the pad sections. The conveyor 10, as shown in Fig. 3, is advanced over the table 25 supported by suitable frame elements indicated generally at 22. Also carried by the frame elements is a tank 83 which contains adhesive. This adhesive may be supplied to the tank in any desired manner and may, if desired, be supplied through conduits indicated generally at 84, 85, so as to provide for circulation of the adhesive, or so as to provide for filling or emptying the tank most conveniently. The applicator roll 86 is journaled as indicated at 87 on suitable frame members and is adapted to close one side of the tank 83. As a result of this, a portion of the applicator roll 86 is at all times in effect inside the tank 83 and is there in contact with the adhesive fluid.

In order to adjust the thickness of the adhesive coating which is allowed to remain on the surface of the applicator roll 86 as it rotates in the direction shown in the arrow of Fig. 3, a doctor blade is slidably supported in suitable guides carried on the bottom of the tank 83 for adjustment toward and away from the applicator roll 86. I have indicated an eccentric shaft 89 adapted to be rotated by a lever 90 for controlling adjustment of the doctor blade 88. Preferably the lever 90 is provided with a spring pressed, manually released button 91 having a portion adapted to enter one of a plurality of arcuately arranged recesses 92. If desired, suitable graduations adjacent each recess 92 may be provided, indicating the resultant spacing between the applicator roll 86 and the doctor blade 88.

Positioned directly beneath the applicator roll 86 is a second roll 93 which is mounted for vertical movement relative to the applicator roll 86. As best seen in Fig. 2, the lower roll 93 is mounted on a shaft 94 by means of suitable bearings, herein indicated as the ball bearings 95. The ends of the shaft 94 are provided with corresponding eccentric projections 96 which are journaled in blocks 97, vertically slideable in elongated recesses 98 provided in brackets 99. The recesses 98 are preferably closed by removable closure plates 100, the closure plates being recessed to position and retain compression springs 101 therein. The blocks 97 previously referred to are correspondingly recessed to receive the opposite end of the compression spring 101. The result will be that blocks 97 and therefore the lower roll 93 will be resiliently urged toward the applicator roll 86. Upward movement of the roll 93 will however be limited by abutment between the blocks 97 and the upper end of the slots 98. In other words, there are means providing for a minimum spacing between the applicator roll 86 and the lower roll 93, but the rolls may be separated further than this minimum spacing by the introduction of a thicker than usual pad, or the like. As a matter of fact, the pads may vary considerably in thickness so that it is desirable to provide for this variable spacing. The minimum spacing, it should be observed, is less than the minimum expected thickness of any pad section. By the foregoing provisions, the compres-

sion between the applicator roll 86 and any thickness of pad will be substantially uniform.

In order to vary the minimum spacing referred to, the shaft 94 has secured thereto at the eccentric portion 96 thereof, a crank 103 provided with a preferably spring pressed, manually releasable button 104 adapted to be received within any one of a plurality of arcuately arranged recesses 105 in an index plate 106 carried by the apparatus. If desired, suitable indicia may be provided adjacent the recesses or apertures 105 to indicate directly the minimum spacing of the roll when the lever 103 is in any given position.

Means are provided for positively driving the applicator roll 86 in timed relation to travel of the conveyor 10. This means takes the form of a sprocket 110, keyed or otherwise secured to the shaft 111 which supports the applicator roll 86. The sprocket 110 is connected to an intermediate driving sprocket 112 by means of a chain 113. In order to drive the intermediate driving sprocket 110 at a rate sufficient to insure synchronous operation of the applicator roll 86, I provide means for driving sprocket 112 from conveyor 10.

Referring now to Fig. 1, the roll 24 which supports the conveyor 10 at one end thereof, is mounted on a shaft indicated at 114, which in turn carries a sprocket 115. Mounted on a suitable support 116 is a shaft 117 carrying a sprocket 118. A chain 119 suitably tensioned around adjustable idle sprockets 120 and 121 interconnects sprockets 115 and 118. As will be evident, if desired, other driving means may be substituted; for example a driving belt rather than a chain drive.

The driving connection for the applicator roll 86 is therefore directly from the conveyor belt 10 to the sprocket 115, to the sprocket 118, to the sprocket 112, to the sprocket 110. As will be evident, by selecting the proper sprocket sizes, the speed of rotation of the roll 86 relative to the travel of the conveyor belt 10 may be as desired. Thus, for example, if it is desired to apply a large amount of adhesive to the pad, the speed of rotation of the applicator roll 86 may be increased relative to the conveyor 10, with the result that substantially more adhesive will be applied. This variation is independent of the second adjustment accomplished by adjustment of the doctor blade 88 previously referred to. In some cases, for example, only a certain thickness of adhesive will cling to the applicator roll, and where it is desired to apply a greater thickness of adhesive to the pad, this may be accomplished by the aforesaid increase of relative speed of the applicator roll.

As best seen in Fig. 4, the sprocket 118 carried by the shaft 117 is loosely mounted for free rotation relative thereto and is adapted to be connected in driving relation to the shaft 117 by means of a clutch construction. This clutch construction comprises a notched hub 120 to which the sprocket 118 is positively secured, and a co-acting clutch member 121 provided with projections 122 adapted to be received within the recesses in the hub 120. The clutch member 121 is keyed to the shaft 117 so that while rotating therewith, it may be axially adjusted therealong. It is further provided with a circular groove 123 which receives fingers 124 of a bifurcated shifter member 125 supported on a suitable bracket 126 on the frame of the machine. As will be evident by the mechanism just described, the positive

rotation of the applicator roll 86 may be interrupted by movement of the clutch member 121 to the left, as shown in Fig. 2, and this may be independent of the continued actuation of the conveyor.

Efforts to apply thick coatings of adhesive to coarse fibrous articles by apparatus similar to this have in the past been hampered by the fact that it was practically impossible to transfer the adhesive from the roll to the pad in the quantities desired. I have found that this transfer in substantially any amount of adhesive may be provided by causing a reverse rotation of the applicator roll relative to travel of the article being coated. It will be seen, for example, that by adjusting the relative speeds of travel of the conveyor and rotation of the roll, the adhesive may be built up to substantially any thickness desired. Further, due to this reverse relative movement between the article being coated and the applicator roll, the adhesive is effectively scraped off of the applicator roll and its transfer does not therefore depend upon a stronger adherence between the adhesive and the article being coated than there is with the applicator roll.

Referring now particularly to Fig. 3, I have shown associated with the applicator roll 86, mechanism for automatically controlling the application of adhesive. This mechanism takes the form of a blade or scraper element 130. The scraper 130, as indicated in this figure, is a separate element bolted or otherwise secured to a receptacle 131 which is pivoted to a bracket 132 as indicated at 133. As best seen in Fig. 2, the receptacle 131 has an inclined bottom portion 134 and is provided with a discharge spout 135. If desired, suitable return conduit means may be provided, or, as an alternative, the adhesive material discharged from the spout 135 may be collected in any suitable container. The receptacle 131 and the scraper 130 are resiliently urged toward the applicator roll 86 by means of a tensioning spring 136.

Carried by the frame of the machine adjacent the conveyor and in advance of the applicator roll 86 are brackets 140 to which is secured a shaft 141 carrying one or more bell crank levers 142. The levers 142 comprise angularly related arms 143 and 144. A link 145 is pivotally connected to the receptacle 131, as indicated at 146, and the other end of the link 145 is pivotally secured to the arm 143 as indicated at 147. The free end of the arm 144 is provided with a roller 148 normally adapted to lie on the conveyor 10. As best seen in Fig. 3, the arm 144 extends at a small angle to the conveyor 10, so that as a pad, such as indicated at 18 in Fig. 4, advances on the conveyor 10, arm 144 is swung in a counter-clockwise direction. There is a corresponding counter-clockwise direction of the arm 143 which is transmitted through the link 145 to swing the receptacle 131 in a clockwise direction. This movement of the receptacle 131, as will be evident, withdraws the scraper 130 from the applicator roll 86 and permits the adhesive to be moved thereby down into position to engage the pad 18.

An important function of the apparatus just described will now be pointed out. In the absence of a scraper element 130, it will be apparent that rotation of the applicator 86, before any pads 18 were brought into juxtaposition thereto, would result in the applicator roll being provided with a film or coating of adhesive completely therearound. Inasmuch as, in order to effec-

tively transfer adhesive to the pad 18, it is necessary to apply at least some pressure thereto, it will be apparent that the advancing edge 18a of the pad 18 would contact the roll 86 somewhere before center. Inasmuch as the applicator roll 86 is preferably rotating in a direction counter to the travel of the pad 18, this would result in scraping off a considerable amount of adhesive material in advance of the leading edge 18a of the pad. This would be highly undesirable since it would represent a waste of adhesive and would further foul both the conveyor belt 10 and the edges of the pads 18.

By providing the automatic mechanism, including the lever 142 and the link 145 and the scraper 130, this undesirable condition can be avoided. The actuating mechanism comprising the lever 142 is positioned relative to the center lines of the rolls 86 and 93 with great exactness. The arrangement is such that the leading edge 18a of a pad 18 serves to move the scraper element 130 away from the applicator roll 86 at the precise instant which will provide a leading edge 150 of a coating of adhesive on the roll 86 to be brought into position substantially adjacent the center line of the rolls 86 and 93 only after the leading edge 18a of the pad 18 has passed a predetermined distance beyond the center line. By this means the accumulation of a gob of adhesive at the leading edge of the pad is avoided.

At the same time, when the trailing edge of the pad has passed the roller 148, the spring 136 will cause the scraper 130 to again engage the roll 86 such that only sufficient adhesive will remain thereon to complete the coating of the pad then in contact with the roll.

The applicator roll 86 is preferably formed of a very smooth material, such as a vitreous material, marble or the like. As a practical matter, I have found that eminently satisfactory results are obtained when the roll is formed of marble. A marble roll may be turned to exact dimensions and finished with the exact smoothness necessary. At the same time this material permits ready transfer of the adhesive from the roll to the article being coated.

While I have illustrated and described only one specific embodiment of my invention, it will be apparent to those skilled in the art that various additions, modifications, omissions, combinations and substitutions may be made which will be within the spirit and scope of my invention as defined by the appended claims.

What I claim as my invention is:

1. In apparatus of the character described, a travelling conveyor, an applicator roll adjacent said conveyor and rotatable reversely relative thereto, a fluid container cooperating with said roll to apply adhesive thereto, and means responsive to the advance of articles on said conveyor to time the advance of fluid on said roll in relation to said articles.

2. In apparatus of the character described, a travelling conveyor, an applicator roll adjacent said conveyor and a rotatable reversely relative thereto, a fluid container cooperating with said roll to apply adhesive thereto, adjustable means for controlling the amount of fluid on said roll, and means effective on said roll at a point after said adjustable means for intermittently removing all fluid therefrom.

3. In apparatus of the character described, a travelling conveyor, an applicator roll adjacent said conveyor and rotatable reversely relative

thereto, a fluid container cooperating with said roll to apply adhesive thereto, adjustable means for controlling the amount of fluid on said roll, and means effective on said roll at a point after said adjustable means for intermittently removing all fluid therefrom, and means for controlling said last means in timed relation to advance of articles on said conveyor.

4. In combination, a travelling conveyor, a fluid supply means, an applicator roll adjacent said conveyor in cooperative relation thereto adapted to receive fluid from said fluid supply means, and control means responsive to the advance of an article on said conveyor to time the advance of fluid on said roll in relation to said article.

5. In combination, a travelling conveyor, a fluid supply means, an applicator roll reversely rotatable relative to travel of said conveyor adjacent said conveyor in cooperative relation thereto adapted to receive fluid from said fluid supply means, and control means responsive to the advance of an article on said conveyor to time the advance of fluid on said roll in relation to said article.

6. In combination, a travelling conveyor, a fluid supply means, an applicator having a surface reversely movable relative to said conveyor, adjacent said conveyor in cooperative relation thereto adapted to receive fluid from said fluid supply means, and control means responsive to the advance of an article on said conveyor to time the advance of fluid on said surface in relation to said article.

7. Applicator means comprising a travelling conveyor, a tank, a roll adapted to engage fluid in said tank, a blade movable toward and away from said roll, and means adapted to be engaged by an article on said conveyor for moving said blade away from said roll in timed relation to advance of said article on said conveyor.

8. Applicator means comprising a travelling conveyor, a tank, a roll adapted to engage fluid

in said tank, a blade movable toward and away from said roll, and means adapted to be engaged by an article on said conveyor for moving said blade away from said roll in timed relation to advance of said article on said conveyor, said means comprising a lever pivoted above said conveyor and connected to said blade.

9. Applicator means comprising a travelling conveyor, a tank, a roll adapted to engage fluid in said tank, a blade movable toward and away from said roll, and means adapted to be engaged by an article on said conveyor for moving said blade away from said roll in timed relation to advance of said article on said conveyor, and resilient means urging said blade toward said roll, whereby fluid will be applied to only such portions of said roll as engage said article.

10. Applicator means comprising a travelling conveyor, a tank, a roll adapted to engage fluid in said tank, and reversely rotatable relative to said conveyor to frictionally engage an article on said conveyor, a blade movable toward and away from said roll, and means adapted to be engaged by an article on said conveyor for moving said blade away from said roll in timed relation to advance of said article on said conveyor.

11. Applicator means comprising a travelling conveyor, a tank, a roll adapted to engage fluid in said tank, a blade movable toward and away from said roll, means for moving said blade, and a separate receptacle associated with said blade for receiving fluid removed by said blade from said roll.

12. In apparatus of the character described, a travelling conveyor, a rotatable applicator roll adjacent said conveyor adapted to engage sheet material carried by said conveyor, means effective to apply adhesive continuously to said roll, and other means actuated by said sheet material for removing adhesive from all portions of said roll except those portions which register with the surface of said sheet material.

CLARENCE J. DAVIES.
